UNITED STATES PATENT OFFICE.

JOSEPH W. MOORE, OF WEST ALLIS, WISCONSIN, ASSIGNOR TO ALLIS-CHALMERS COMPANY, OF MILWAUKEE, WISCONSIN, A CORPORATION OF NEW JERSEY.

CYLINDER-LINER.

982,739.

Specification of Letters Patent. Patented Jan. 24, 1911.

Application filed November 17, 1910. Serial No. 592,903.

To all whom it may concern:

Be it known that I, JOSEPH W. MOORE, a citizen of the United States, residing at West Allis, in the county of Milwaukee and State of Wisconsin, have invented a certain new and useful Improvement in Cylinder-Liners, of which the following is a specification.

This invention relates to improvements in the construction of engine cylinders and more particularly to the construction of bushings or liners and means for fastening same to the interior walls of the cylinders.

The object of the invention is to provide a simple and efficient means for attaching liners to cylinder walls.

In the manufacture of pumping engine, gas engine or steam engine cylinders, it has been found difficult especially in the larger sizes, to obtain cast metal on the interior working surfaces of the cylinders, which is free from foreign matter or defects such as slag and blow holes. To overcome this difficulty it has been customary to counter-bore the cast metal cylinder and insert a wearing liner therein. These inserted liners are usually shrunk into position within the cylinder bore by simultaneously heating the cylinder wall and cooling the liner, and after inserting the liner within the cylinder, causing a sudden reverse change of temperature in the members.

The manufacturers of cylinders having the shrunk-in liners have been confronted with the difficulty of preventing end displacement of these liners, due to the reciprocation of the piston thereover, and it is the object of the present invention to obviate this difficulty by positively locking the members together.

A clear conception of one embodiment of the invention can be obtained by referring to the accompanying drawing in which like reference characters designate the same or similar parts in the various views.

Figure 1 is a fragmentary central vertical section through a gas engine cylinder wall showing a shrunk-in liner in position therein. Fig. 2 is a transverse vertical section through the cylinder wall and liner shown in Fig. 1, the section being taken through the displacement preventing lugs formed on the cylinder wall. Fig. 3 is a fragmentary longitudinal sectional enlarged view of the cylinder wall and lining members.

The cylinder 1 has a hollow cylindrical central one-piece bearing wall member, and may be of any desired construction, depending upon the type of engine with which it is to be used. The bushing or liner 32 which constitutes the lining member of the cylinder, has portions 3, 2, of different diameters on either side of its mid-portion. As shown, the portion 3 is of somewhat larger external diameter than the portion 2. Inwardly projecting radial pads or lugs 4 are formed in one with the wall of the cylinder 1 adjacent the mid-portion thereof. Outwardly projecting radial pads or lugs 5 are formed in one with the liner 32 adjacent the mid-portion thereof. The pads or lugs 4, 5, are of substantially equal dimensions and are of less circumferential length than the recesses or spaces 6 formed between them.

In constructing the cylinder 1, the cylinder wall member is bored to two diameters, the one slightly less than the outside diameter of the liner portion 2, and the other or counter-bore slightly less than the outside diameter of the liner portion 3. The larger bore extends into the wall member of the cylinder 1, to the pads or lugs 4.

The one-piece lining member or liner 32 is formed with a through bore and has its portions 3, 2, turned to outside diameters which are slightly larger than the inside diameters of the larger and smaller bores, respectively, of the wall member of the cylinder 1.

With the cylinder wall member and liner 32 thus properly machined and ready for coaction, the wall member of the cylinder 1 is heated to a high degree of temperature by means of steam admitted to the jacket surrounding the said wall member, thus causing the wall to expand. False heads inserted into the ends of the lining member or liner 32 form a closed chamber which is filled with a cold medium, such as water, thus causing the liner to contract. The heating of the wall member of cylinder 1 causes the diameters to increase while the cooling of the liner 32 causes its diameters to decrease, so that the liner 32 can be inserted freely into the bore of the cylinder 1. With the members thus relatively expanded and contracted, the liner 32 is inserted longitudinally within the wall of the cylinder 1 until the outwardly projecting lugs 5 of the liner 32 have passed the inwardly projecting lugs 110

4 of the cylinder 1, and coact against the end of the counter-bore portion of the cylinder wall having least diameter. Such insertion is made possible since the outwardly projecting lugs 5 of the lining member or liner 32 can pass freely through the recesses or spaces 6 formed intermediate the inwardly projecting lugs 4 of the wall member of the cylinder 1, while the inwardly projecting lugs 4 pass freely through the recesses or spaces 6 intermediate the outwardly projecting lugs 5 of the lining member or liner 32.

Upon having passed the inwardly projecting lugs 4 with its outwardly projecting lugs 5, the liner 32 is given a partial rotation until the adjacent lugs 5 of the liner and lugs 4 of the cylinder 1 are brought in alinement with each other as shown in Fig. 1. The steam jacket is then removed from the cylinder wall while the cooling medium is removed from the interior of the liner 32. This sudden change in temperature in the wall of the cylinder 1 and liner 32 causes the members to contract and expand respectively, thereby bringing them into firm coaction with each other.

The spaces 6 exist between the assembled parts by reason of the registering of the lugs 4, 5, the spaces between the lugs 4 on the cylinder 1 and between the lugs 5 on the liner 32 constituting these spaces 6. The spaces 6 are formed between the lugs by chipping or planing away the metal. In order to allow the entrance of the lugs 4 into that part of the groove adjacent the lugs 5, noting that during assembling the members the lugs 4 on the cylinder 1 are longitudinally expanded and the groove on the liner adjacent the lugs 5 is longitudinally contracted, the end faces of the lugs 4 and the corresponding end faces of the grooves adjacent the lugs 5 are similarly slanted instead of being cut at right angles to the axis of the members. This slanting of the lugs 4 need only be at one end thereof and at the corresponding end face of the groove. Entry is thus easily effected, the members being slightly radially spaced adjacent the lugs 4 during assembling of the members. The restoration of the members to their normal temperatures will destroy this radial spacing and lock same firmly together.

It will be noted that with the lugs 4, 5, in alinement with each other, the possibility of the liner 32 being displaced longitudinally of the cylinder 1 by the reciprocation of a piston thereon, is entirely eliminated. By forming a longitudinal displacement preventing means near the mid portion of the wall member of the cylinder 1, a free relative expansion and contraction of the portions 3, 2, of the lining member or liner 32 is permitted. Provision for such free

relative motion of the members is necessary since the liners are often constructed of a different material than the cylinder itself, the several materials used having different coefficients of expansion.

It should be understood that it is not desired to be limited to the exact details of construction shown and described, for obvious modifications will occur to a person skilled in the art.

It is claimed and desired to secure by Letters Patent,—

1. In a cylinder, a wall member and a lining member, a projecting lug at the mid portion of each of said members, said lug on said wall member adapted to be placed in longitudinal alinement with said lug on said lining member to lock said members together.

2. In a cylinder, a wall member and a lining member, a lug having a space circumferentially adjacent thereto at the mid portion of each of said members, the lug of one member being of less circumferential length than the space adjacent the lug of said other member.

3. In a cylinder, a liner having portions of different diameters, and a lug formed on a portion of smaller diameter than the portion of maximum diameter.

4. In a cylinder liner, a wall member and a lining member, a lug projecting from the mid portion of each of said members, and means for permitting the insertion of said lining member within said wall member to bring said lugs in longitudinal alinement.

5. In a cylinder liner, a wall member and a lining member, means projecting from each of said members, said means being longitudinally registrable and having slanting coacting end faces.

6. In a cylinder liner, a wall member and a lining member, means projecting from one of said members and having a slant end face coacting with a slant end face on the other of said members.

7. In a cylinder liner, a wall member and a lining member, a lug projecting from said wall member and having a slant end face coacting with a slant end face on said lining member.

8. A bored and counter-bored cylinder, a liner fitting said bore and counter-bore, the end of said counter-bore forming an abutment for the liner, and means projecting from the cylinder short of the end of the counter-bore and coacting with a slant end face on the liner.

In testimony whereof, I affix my signature in the presence of two witnesses.

JOSEPH W. MOORE.
